US0D1070462S

(12) United States Design Patent (10) Patent No.: US D1,070,462 S
(45) Date of Patent:  Apr. 15, 2025

(54) COFFEE MACHINE

(71) Applicant: Guido Pozzolini Gobbi Rancilio,
Lugano (CH)
(72) Inventor: Guido Pozzolini Gobbi Rancilio,
Luxembourg (LU)

() Term: 15 Years

(21) Appl. No.: 35/517,469

(22) Filed: May 26, 2023

(80) Hague Agreement Data

Int. Filing Date: May 26, 2023
Int. Reg. No.: DM/229245
Int. Reg. Date: May 26, 2023
Int. Reg. Pub. Date: Jun. 9, 2023

(30) Foreign Application Priority Data

Nov. 29, 2022 (CH) 2022-00607
